UNITED STATES PATENT OFFICE

FAYE E. DONOVAN, OF MODESTO, CALIFORNIA

DESIGN FOR A SMOKER'S STAND

Application filed March 16, 1932. Serial No. 43,211. Term of patent 7 years.

To all whom it may concern:

Be it known that I, FAYE E. DONOVAN, a citizen of the United States, residing at Modesto, in the county of Stanislaus and State of California, have invented a new, original, and ornamental Design for a Smoker's Stand, of which the following is a specification, reference being had to the accompanying drawing, forming part thereof. The figure on the drawing is a perspective view of a smoker's stand, showing my new design.

I claim:

The ornamental design for a smoker's stand, as shown.

FAYE E. DONOVAN,
